UNITED STATES PATENT OFFICE.

WAYNE MCKENZIE STEVENS, OF TAYLORVILLE, ILLINOIS.

GRAIN-SHOCKER.

1,248,943

Specification of Letters Patent.

Patented Dec. 4, 1917.

Application filed March 13, 1917. Serial No. 154,612

To all whom it may concern:

Be it known that I, WAYNE MCKENZIE STEVENS, a citizen of the United States, and resident of Taylorville, in the county of Christian and State of Illinois, have invented a certain new and useful Grain-Shocker, of which the following is a specification.

The object of my invention is to provide a grain shocker for bundles of small grain adapted to be mounted on an ordinary grain binder.

A further object is to provide a device adapted to receive and press a number of bundles together and to remove said bundles from the receiving portion of the mechanism and place them on the ground heads up in a shock.

A further object is to provide in such a machine suitable mechanism for timing the mechanism of the various parts whereby the bundles may be gripped at the proper time and removed from the receiving mechanism at the proper time and entirely discharged from the machine in proper sequence.

With these and other objects in view, my invention consists in the construction, arrangement and combination of the various parts of the device, whereby the objects contemplated are attained, as hereinafter more fully set forth, pointed out in my claims, and illustrated in the accompanying drawings, in which:

Figure 1 shows a top or plan view of my grain shocker mechanism.

Fig. 2 shows a detail, sectional view of part of the mechanism.

Fig. 3 shows a side elevation of my device.

Fig. 4 shows a longitudinal, sectional view of the telescoping members.

Fig. 5 shows a rear elevation of the device, showing the parts of the binder illustrating the relative position of my device with relation to the bundle handling mechanism of the binder.

Fig. 6 shows a top or plan view of two of the shafts with the gearing devices thereon.

Fig. 7 shows a horizontal, sectional view of a part of my bundle handling mechanism.

Fig. 8 shows an end view of three of the shafts, with part of the mechanism thereon, and

Fig. 9 shows a sectional, detail view of part of the mechanism.

In the accompanying drawings, I have

shown in Fig. 5, a part 10 of a binder frame which supports the elevating mechanism and is arranged over the large tractor wheel 11 from which the ordinary mechanism of the binder is run. I have indicated part of such mechanism 12.

I have used the numeral 13 to indicate generally the frame of my improved attachment, which is supported upon the main frame, and upon an axle 14, upon which are 65 wheels 15.

Supported on the frame 13 at such point as to receive bundles, leaving the kickoff mechanism 16, is a bundle receptacle having the spaced side walls 17 and 18, which are 70 curved toward each other at their lower ends, as clearly shown in Fig. 5.

The wall 18, which is farther from the kickoff mechanism, and is laterally in the machine therefrom, is higher than the wall 75 17 so as to facilitate the feeding of the bundles to the bundle receptacle.

At its forward end the receptacle has a wall 19, and at its rearward end is a wall 20 hinged at its lower end and normally held in 80 closed position by means of a spring 21.

Supported near the rear lower part of the bundle receptacle are parallel, longitudinally, arranged spaced tubes 22, which are supported below the bundle receptacle 85 and are connected by a suitable frame member 23 for holding them properly spaced and rigidly supported.

Telescopically mounted in each tube 22 is a smaller tube 24, the forward end of which 90 normally stands below the forward portion of the bundle receptacle, and has a cap 25 for limiting the rearward telescoping movement of said tubes 24 in the tubes 22.

Mounted on the rear end of each tube 24 95 is a frame member 26, which extends outwardly and upwardly in the machine and upwardly and then rearwardly in the machine as shown in Figs. 1 and 3.

The rear ends of the frame members 26 100 carry supporting caster wheels 27.

For normally holding the tubes 24 in their forward positions, I have provided in each of said tubes a longitudinally sliding rod 28. Pivoted to each tube 24 is a pawl 29, the engaging end of which is adapted to project through a hole 30 in the wall of the tube 24, which pawl 29 has an arm pivoted to the rod 28, as shown in Fig. 4, said arm being yieldingly held by a spring 31 in position 110

for causing the engaging end of the pawl 29 to project through the opening 30, and in the forward position of each tube 24, the pawl 29 engages the forward end of the tube 22 and prevents any rearward movement of the tube 24 with relation to the said tube 22. The rod 28, when the pawl is in the last described position, projects through the rear end of the tube 22 a short distance and extends forwardly from the pawl 29 toward the forward end of the tube 24 terminating short of said end, as shown in Fig. 4. The forward end of the rod 28 is pivoted to an upwardly extending arm on a pawl 32, which arm may also slide on the rod 28. The engaging end of said pawl 32 is designed to extend in certain of its positions through an opening 33 in the wall of the tube 24. On the rod 28, rearwardly from the pawl 32, is a collar 34, and between the collar 34 and the arm of the pawl 32, which is pivoted on the rod 28, is a spring 35 which tends to normally hold the arm on the pawl 32 in its forward position.

It will be seen that the engagement of the pawls 29 with the forward ends of the tubes 22 will lock the tubes 24 in the forward positions of their movement.

Formed on the frame members 26 are opposite fixed toothed sprocket gears 36. The frame members 26 also form bearings for a transverse shaft 37. On the shaft 37 is mounted a sleeve 38 between the fixed sprocket gears 36. The sleeve 38 is fixed to the shaft 37.

Pivoted to each sleeve 38, near its ends, are the lower forked members 39 of an arm 40, which normally extends upwardly and forwardly in the machine with its forward end outside to and spaced from one of the walls 17 or 18, near the central part thereof, as shown in Figs. 1, 3, and 7.

The arms 40 are pivoted so that their free ends may swing laterally in the machine.

Supported on each arm 40 is a bundle gripper 41, as shown in Figs. 5 and 1.

The side walls 17 and 18 are provided with central, vertical slots 42 to permit said bundle grippers 41 to enter the bundle receptacle.

Each gripper 41 is mounted upon a transverse, horizontal shaft 43, rotatably mounted in the free end of the arm 40, which shaft, when the free ends of the arms 40 are at the inner limit of their movement, is adapted to travel upwardly and rearwardly through a slot 44 in the wall 18 or 17, as the case may be, when the arm is swung upwardly and rearwardly on its pivot while holding the gripper 41 within the bundle receptacle during such swinging movement.

On the outer end of each shaft 43 is a sprocket gear 45. A chain 46 is mounted on each sprocket gear 45 and on one of the fixed sprocket gears 36.

On each arm 40 is a bracket 47. Secured to each bracket, 47 is a chain 48, which extends rearwardly in the machine and is secured to the frame member 26, as shown in Fig. 3, for limiting the forward and downward movement of the arm 40.

Pivoted to one of the arms 40 rearwardly of the bundle receptacle is a tube or sleeve 49. Pivoted to the other of said arms 40 is a rod or the like 50, telescopically received within the tube or sleeve 49 and having formed at its free end teeth 51.

Pivoted upon the tube 49 is a pawl 52, the engaging end of which is designed, in certain positions of said pawl, to extend through an opening 53 in the tube 49 and engage the teeth 51 for preventing the movement of the arms 40 away from each other.

A rod 54 is pivoted to an upwardly extending arm of the pawl 52, and slidably extended through a bracket 55.

Mounted on the rod 54 is a spring 56, which tends to yieldingly hold the pawl 52 in its position for engaging the teeth 51. On the tube 49 is a collar 57 and between the collar 57 and the arm 40 to which the rod 50 is secured, is a powerful coil spring 58 tending to yieldingly hold the arms 40 away from each other.

It is my purpose to have the bundles discharged from the kickoff mechanism 16 into the bundle receptacle and when the bundle receptacle is filled, to actuate mechanism for causing the bundle grippers to move inwardly toward each other for gripping between them the bundle in the bundle receptacle, thereupon the mechanism is operated for swinging the bundle grippers with the bundles received between them upwardly and rearwardly and for placing the bundles in proper position on the ground rearwardly of the machine.

I shall now describe more in detail the mechanism for accomplishing these operations.

Suitably supported on the frame 13, at the lower rear end of the bundle receptacle, is a transverse shaft 59, above which is a transverse shaft 60. Rearwardly in the machine from the shaft 59 is a transverse shaft 61, and rearwardly from the shaft 61 is a shaft 37, already mentioned.

Operatively connected with the tractor wheel 11 is a gear 62 in mesh with a gear 63 on the shaft 59.

The bundle grippers 41 normally stand outside the bundle receptacle. For moving them inwardly, the following mechanism is provided.

I have already described the tubes 49 and rod 50 and some of the parts connected therewith.

Slidably but non-rotatably mounted on the shaft 60 is a sleeve 81, having at one end

an annular disk 82 provided at one point in its circumference near its periphery with a pocket 83. Arranged adjacent to the disk 82 is a roller 84 supported by a bracket 85 on the frame 13, and adapted to travel on the face of the disk 82 when the sleeve 81 and the disk 82 are rotated. The disk 82 normally stands in such position on the shaft 60 that the roller 84 is received in the pocket 83 (see Figs. 6 and 9).

Formed on the end of the sleeve 81, opposite the disk 82 is a clutch member 86. Rotatably but non-slidably mounted on the shaft 60 near the clutch member 86 is a gear 87 having formed on one side a clutch member 88 adapted to coact with the clutch member 86.

The gear 87 is in mesh with a gear 89 on the shaft 59.

For throwing the clutch members 86 and 88 into gear, the following means has been provided.

The clutch member 86 has a smooth face engaged by one end of a pivoted arm 89^a. Secured to the arm 89^a is a rope 90 extended over a guide pulley 91, thence over a guide pulley 92, and then secured to a lever 93 on the frame of the binder. By moving the lever 93 in one direction, the arm 89^a, shown in Fig. 6, will be operated for forcing the clutch members 86 and 88 into engagement with each other. A spring 94 normally holds the clutch members 86 and 88 out of engagement with each other.

Fixed on the shaft 60 is a cam 95 having a continuous groove 96 in its face, formed with central, right-hand and left-hand stretches, as shown by full and dotted lines in Fig. 6, and by full lines in Fig. 5.

Slidably but non-rotatably mounted on the shaft 59 is a double clutch member 97. Pivottally connected on the frame 13 is an arm 98, which is operatively connected with the double clutch member 97, and has one end extended into the groove 96. Rotatably but non-slidably mounted on the shaft 59, on opposite sides of the clutch 97, are gears 99 and 100.

The gear 99 meshes with a gear 101 on the shaft 61, and the gear 100 meshes with a gear 102 on a sleeve 103 on the shaft 61.

On the sleeve 103 is a gear 104 which meshes with a gear 105 fixed on the sleeve 38, which sleeve is fixed on the shaft 37. On the shaft 61 is a gear 106 in mesh with a gear 73 on the sleeve 38. On the sleeve 38 are fixed the arms of a yoke 72 (Fig. 7).

Loosely mounted on the sleeve 38 between said arms is the gear 73 having formed on one face a frictional clutch member 74. Loosely mounted on the sleeve 38, between the gear 73 and one of the arms of the yoke 72 is a drum 75, having formed at one end a frictional clutch member 76 adapted to coact with the clutch member 74.

On the opposite end of the drum 75 is fixed a disk 77. Screwed through one arm of the yoke 72 are screws or screw-threaded bolts 78, the ends of which engage the disk 77 for regulating the tension between the clutch members 74 and 76.

Wound on the drum 75 are ropes 79 which extend around pulleys 80 supported by the yoke 72 and are secured to the respective arms 40. It will be seen that by winding the ropes 79 on the drum 75, the arms 40 will be drawn toward each other for thereby drawing the bundle grippers toward each other.

On the shaft 59, not far from the gear 89^a, is loosely mounted a drum 64, on one end of which is a clutch member 65.

Slidably but non-rotatably mounted adjacent to the clutch member 65, is a clutch member 122 on the shaft 59.

Wound on the drum 64 are two ropes or other flexible device 67, which are extended forwardly and upwardly in the machine around guide pulleys 68, and thence laterally in the machine around guide pulleys 69 and 70 (Fig. 1), on opposite sides of the forward end of the bundle receptacle, and thence rearwardly in the machine to the respective shafts 43, to which ropes are secured by means of loose collars 71, shown in Fig. 1.

The ropes 67, and parts connected therewith, serve to return the arms 40 to their normal positions, as shown in Fig. 3, after the shock has been deposited on the ground, and their operation will be hereinafter more fully referred to.

On each outer end of the shaft 38 is mounted a hub or the like 107, having a recess 108 in its outer end. Each hub 107 is adapted to rotate, but its rotation is limited by a spring 109 secured to the hub and to the shaft, and adapted when the shaft is in normal position when the arms 40 extend forwardly and upwardly in the machine to hold the hub 107, which has the arm 110 thereon, in position for holding the arm upwardly, as shown in Fig. 7. The arm 110 extends in such position upwardly and inwardly in the machine and has on its free end a head 111, adapted when the shaft 38 is rotated in one of its positions, to engage the rearward end of the rod 28 for moving the rod 28 a short distance forwardly in the machine, until the head 111, engages the rearward end of the tube 24.

Secured to the rod 54 is a rope or the like 113, which is extended over a guide pulley 114, and through a guide ring 115, and is secured to the frame at a suitable point as at 116 (Fig. 5), and is arranged with considerable slack when the parts are in their normal positions.

I will now describe the practical operation of my improved shock device.

Normally the arms 40 stand in the position shown in Fig. 3, extending upwardly and forwardly in the machine, and the grippers 41 stand just outside the bundle receptacle. The bundles are fed from the kickoff mechanism 16 downwardly into the bundle receptacle, until the bundle receptacle is filled as full as the operator desires. The operator then grasps the lever 93, and pushes it toward the frame member to which it is secured, thereby moving the arm 89 toward the smooth face of the clutch member 86 for moving the clutch member 86 into engagement with the clutch member 88.

15 The shaft 59 is constantly rotated from the traction wheel of the binder.

When the clutches 86 and 88 are thrown into engagement, the gear 89 in mesh with the gear 87, will cause said gear to rotate,

20 thereby rotating the shaft 60 through the clutch member 86, which is fixed to said shaft. The parts are so arranged that at the beginning of each operation, when the shaft 60 begins to rotate, the free end of

25 the arm 98 travels into the left-hand portion of the groove 96, thereby throwing the clutch member 97 into engagement with a coacting clutch member 112 on the gear 99, thereby causing the gear 99 to be rotated.

30 The gear 99 is in mesh with the gear 101 on the shaft 61. The shaft 61 is thereby rotated for rotating the gear 106 and the gear 73 in mesh therewith. The rotation of the gear 73 through the clutch members 74 and 35 75 rotates the drum 76, winding the ropes 79 thereon for drawing the arms 40 toward each other.

The movement of the arms 40 toward each other moves the grippers 41 toward each 40 other, through the slots 41 in the sides of the bundle receptacle.

When the shafts 40 move toward the inward limit of their movement, they are held by the pawl 52 which engages the teeth 51 45 on the member 50. It will be seen that slippage is permitted by the clutch members 74 and 76 to make allowance for differences in the size of the bundles and the number of bundles in the bundle receptacle.

50 The head of the arm 98 then moves into the right-hand portion of the slot 96, thereby moving the clutch member 97 out of engagement with the clutch member 112, and into engagement with a clutch member 117

55 on the gear 100. The gear 100 is in mesh with the gear 102 on the sleeve 103. The sleeve 103 is thereby rotated for imparting rotation to the gear 104 and to the gear 105 in mesh therewith. The rotation

60 of the gear 105 rotates the sleeve 38 in the shaft 37 for swinging the arms 40 upwardly and rearwardly. During such movement, the shafts 43 travel upwardly through the curved slots 44 until they leave the bundle receptacle, carrying with them the grippers

65 70 pers 41 and the bundles held between said grippers. The bundles are fed into the receptacle with their heads to the rear. The movement of the arms 40 continues until they extend rearwardly and slightly upwardly, as illustrated by dotted lines in Fig. 3.

During the movement of the arms 40 from their position shown by full lines in Fig. 3 to their position shown by dotted lines in said figure, it will be seen that insomuch as the gears 36 are fixed, some rotation will be imparted to the gears 45 for swinging the butts of the bundles downwardly and rearwardly, until when the arms 80 40 are in their rearwardly extending position, the bundles which are indicated by the numeral 118, stand in the position shown in Fig. 3.

When the arms 40 reach their rearward position, the heads 111 on the arms 110 engage the rearward ends of the rods 28, thereby moving said rods forwardly in the machine and freeing the pawls 29 from engagement with the forward ends of the tubes 22, and thereby permitting the springs 31 to raise the pawls 29, so that the tubes 24 may slide rearwardly in the tubes 22.

The rearward movement of the rods 28 tends to draw the engaging ends of the 95 pawls 32 through the openings 33 in the tubes 24. The faces of said engaging portions, which would engage the forward ends of the tubes 22, are beveled so that as the pawls 32 strike the forward ends of the 100 tubes 22 they are pushed upwardly into the tubes 24, against the pressure of the spring 35. When, however, the pawls 32 leave the rearward ends of the tubes 22, the springs 35 force the forward ends of said pawls 105 downwardly so that said pawls will then prevent any forward movement of the tubes 24 in the tubes 22 until the pawls 32 are again raised.

The action of the parts is so timed that 110 the shock is firmly set on the ground, and is held for a short time during the rearward sliding movement of the tubes 24, and when the tubes reach their rearward limit of movement, the rope 113 becomes taut, thereby releasing the pawl 52, whereupon the spring 58 forces the arms 40 apart, whereupon the parts assume the position shown by dotted lines in Fig. 1.

On the shaft 60 is a cam 120, having in its surface a cam-shaped slot 121. The arm 123 is pivoted on the frame of the machine and is operatively connected with the clutch member 122, and has its free end received in the slot 121.

When the last described point in the operation of the machine has been reached, the end of the arm 123, reaches the position in the slot 121 where the arm 123 is moved to position for causing the clutch members 122 125 130

and 65 to engage for thereby imparting rotation to the drum 64 and winding the rope 67 onto said drum, thereby raising the arms 40, and giving them their forward movement.

When the arms 40 reach the position extending substantially upwardly, the heads 111 on the arms 110 move away from the rearward ends of the rods 28, permitting the springs 31 to move the rods rearwardly in the machine, thereby releasing the pawls 32.

The arms 40 continue their forward movement until they reach the position where the chains 48 become taut for holding the arms 40 in position, extending upwardly and forwardly in the machine, and thereupon the continuous winding of the rope 67 on the drum 64 draws the tubes 24 and the parts supported thereon forwardly in the machine until the pawls 29 pass and clear the forward ends of the tubes 24, and drop into the openings 30 in the tubes 24, at which time the arms 40 stand in the position, shown in Fig. 3, with the grippers outside the bundle receptacle.

At this time in the operation of the machine, the free end of the arm 123, reaches another portion of the cam slot 121, whereby the clutch member 122 is moved out of engagement with the clutch member 65.

At the same time, the slot 83 in the face of the disk 82 reaches the roller 84, whereupon the spring 94 forces the sleeve 81 laterally for moving the clutch member 86 out of engagement with the clutch member 88.

During the time when the drum 64 is being rotated, the free end of the arm 98 travels in the central portion of the slot 96, thereby holding the double clutch member 97 in its neutral position.

It should be noted that when the rearward sliding movement of the tubes 24 begins, the gears on the shaft 61 are moved out of mesh with the gears on the shaft 59, and when the parts are returned to their normal position, the gears on the shaft 61 are returned to mesh with the gears on the shaft 59.

It might be mentioned in this connection that during the first part of the upward and rearward movement of the arms 40, the grippers will engage the upper portion of the hinged door 20 and swing said door rearwardly against the pressure of the spring 21. As soon as the bundles clear the door 20, the spring 21 returns said door to its closed position.

It will have been noted that when the bundles are moved toward position for being left on the ground, they are dropped on the ground and are then held for a short time, so that they will not be upset by any momentum they may have received during the rearward swinging movement of the arms 40.

This gives the straw also a chance to set in position before the bundles are released by the grippers.

Owing to the fact that the length of the bundle receptacle fore-and-aft should be changed in order to cause bundles of different lengths to fit and lie properly in the receptacle, I have made the front wall 19 narrower than the bundle receptacle as illustrated in Fig. 1.

Suitably mounted at one side from the bundle receptacle, near the forward end thereof, are two upright rock shafts 200 and 201. On the shaft 200 are a pair of curved, spaced arms 202 extending to position in front of the bundle receptacle.

On the shaft 201 is a similar pair of curved spaced arms 203 arranged parallel with the respective arms 202. A rearwardly extending bar 204 is secured to the forward surface of the wall 19, and is pivotally connected with the arms 202 and 203.

On the shaft 201 is a laterally extending arm 205, to which is pivoted a rod 206 extending rearwardly in the machine. The rod 206 is pivoted at its rear end to one arm of a centrally pivoted bell crank lever 207.

Pivoted to the other arm of the bell crank lever 207 is a rod 208 extending laterally in the machine and secured to a lever 209.

The lever 209 has a pawl 210, adapted to coact with a sector 211. By manipulating the lever 209, the wall 19 may be shoved inwardly or outwardly in the bundle receptacle.

Some changes may be made in the construction and arrangement of the parts of my improved machine without departing from the essential features and purposes of my invention, and it is my intention to cover by my present application, any such modified forms of structure or use of me hasical equivalents, which may be reasonably included within the scope of my claims.

I claim as my invention:

1. In a device of the class described, a receptacle for receiving bundles, a frame mounted for sliding movement with relation to said receptacle, arms pivoted thereon rearwardly of said receptacle, and adapted in one of their positions to extend upwardly and forwardly in the machine, said arms being capable of pivotal movement in a vertical plane, and also of movement toward and from each other, gripper devices carried by said arms, said receptacle being provided with openings to receive said gripper devices, means for moving said gripper devices toward each other for gripping between them bundles in the bundle receptacle, means for swinging said arms rearwardly on their pivot points, wheels for supporting one end of said movable frame, means for holding said movable frame at the forward limit of its movement, means for releasing

said means, when said arms reach a certain position of their rearward movement, means for moving said arms apart after they have reached their rearward limit of movement, and means for returning said arms to their original position.

2. In a device of the class described, a receptacle for receiving bundles, a frame mounted for sliding movement with relation to said receptacle, arms pivoted thereon rearwardly of said receptacle, and adapted in one of their positions to extend upwardly and forwardly in the machine, said arms being capable of pivotal movement in a vertical plane, and also of movement toward and from each other, gripper devices carried by said arms, said receptacle being provided with openings to receive said gripper devices, means for moving said gripper devices toward each other for gripping between them bundles in the bundle receptacle, means for swinging said arms rearwardly on their pivot points, wheels for supporting one end of said movable frame, means for holding said movable frame at the forward limit of its movement, means for releasing said means, when said arms reach a certain position of their rearward movement, means for moving said arms apart after they have reached their rearward limit of movement, and means for returning said arms to their original positions, and for sliding said movable frame forwardly in the machine to its original position.
3. In a device of the class described, a receptacle for receiving bundles, a frame mounted for sliding movement with relation to said receptacle, wheels on said frame for supporting one end of said frame on the ground, means for locking said frame in its forward position of movement, arms pivotally mounted on said frame, rearwardly of said bundle receptacle, and designed to extend normally upwardly and forwardly in the machine, bundle grippers on said arms, means for swinging said arms toward each other, means for swinging said arms rearwardly in the machine, means for releasing said holding means when said arms have reached their rearward positions, means for imparting to said arms limited rotary motion during their rearward movement, and means for returning the parts to their original positions.
4. In a device of the class described, a receptacle for receiving bundles, a frame mounted for sliding movement with relation to said receptacle, wheels on said frame for supporting one end of said frame, on the ground, means for locking said frame in its forward position of movement, arms pivotally mounted on said frame rearwardly of said bundle receptacle, and designed to extend normally upwardly and forwardly in the machine, bundle grippers on said arms,

means for swinging said arms toward each other, means for swinging said arms rearwardly in the machine, means for releasing said holding means when said arms have reached their rearward positions, means for imparting to said arms limited rotary motion during their rearward movement, means for moving said arms apart after they have reached the rearward limit of their movement, means for swinging said arms forwardly in the machine, and means for returning said movable frame to its original position.

5. In a grain shock machine, a bundle receptacle having openings in its side walls, bundle grippers, means for moving said bundle grippers through said openings from the outside to the inside of said receptacle, means for moving said gripper to position for depositing said bundle on the ground, and means for returning said grippers to their original position.

6. In a device of the class described, the combination of a grain binder machine, with a receptacle adapted to receive bundles dropped therefrom in a horizontal position, a frame mounted for fore-and-aft sliding movement in the machine, arms mounted on said frame, for pivotal movement in two directions, grippers on the free ends of said arms mounted for rotary movement, means for swinging the free ends of said arms inwardly for gripping bundles in said receptacle, and for thereafter simultaneously swinging said arms upwardly and rearwardly and for rotating said grippers, and for thereafter swinging said arms downwardly and depositing said bundles on the ground, means for normally holding said movable frame in its forward position, means for releasing said last means when said arms are in their last described position for permitting the machine to move forwardly without disturbing said bundles after the bundles have been placed on the ground, whereby the grippers may hold the bundles for a short period of time after the bundles are deposited on the ground, and means for thereafter spreading the opposite ends of said arms apart and returning them to their original positions.

7. In a device of the class described, a receptacle, a frame, arms pivoted on said frame rearwardly of said receptacle, grippers on said arms, means for moving said arms to position for gripping bundles in said receptacle, means for swinging said arms upwardly and rearwardly and thence downwardly and rearwardly and, thence downwardly for depositing said bundles on the ground, said receptacle having a rear wall pivoted at its lower edge, and means for yieldingly holding said wall in its upright position.

8. In a device of the class described, a re-

130

ceptacle for receiving bundles from a binder, a movable frame device having a wheel rearwardly of said receptacle, said frame device being capable of sliding movement with 5 relation to said receptacle, means for locking said frame device in its forward position of movement, gripping devices movably mounted on said frame device, means for moving said gripping devices to position 10 for engaging bundles in said receptacle, means for moving said gripping devices to position for depositing bundles on the ground, means for releasing said means, means for releasing said locking device for permitting said frame device to remain stationary with relation to the ground while the receptacle moves forwardly with a binder, means for moving said gripping device apart, and means for returning said gripping devices and movable frame device 15 to their original positions.

Des Moines, Iowa, February 1, 1917.

WAYNE MCKENZIE STEVENS.
